UNITED STATES PATENT OFFICE.

WILLIAM A. CAMPBELL, OF MARCELINE, MISSOURI, ASSIGNOR OF ONE-HALF
TO W. S. HAYDEN AND EDWARD H. TAYLOR, OF SAME PLACE.

DEHORNING IMPLEMENT.

SPECIFICATION forming part of Letters Patent No. 468,236, dated February 2, 1892.

Application filed September 19, 1891. Serial No. 406,217. (No model.)

To all whom it may concern:

Be it known that I, WILLIAM A. CAMPBELL, a citizen of the United States, residing at Marceline, in the county of Linn and State of Missouri, have invented certain new and useful Improvements in Dehorning-Instruments; and I do hereby declare the following to be a full, clear, and exact description of the invention, such as will enable others skilled in the art to which it appertains to make and use the same.

My invention has relation to improvements in implements for dehorning cattle; and it has for its general object to provide such an implement embodying a construction where-
15 a great leverage and strong cutting power may be attained.

To the attainment of the foregoing and other objects the invention consists in the peculiar construction, certain novel combina-
20 tions, and the adaptation of parts hereinafter described and claimed.

In the accompanying drawings, Figure 1 is a plan view of my improved implement with one of the covering or bearing plates partly broken away, and Fig. 2 is an enlarged trans-
25 verse section taken in the plane indicated by the line $x-x$ on Fig. 1 with both of the plates in position.

Referring by letter to the said drawings, A
30 indicates the main bar of my improved imple-
ment, which is preferably of a rectangular
form in cross-section for a portion of its length
for the attachment of the covering and bear-
ing plates B, which are connected to said bar
35 by rivets, as a , or in any other manner suit-
able to the purposes of my invention. These
parallel plates B, which are preferably of the
approximate form illustrated and are de-
signed to afford bearings for the operative
40 parts of my implement, are provided at a
point adjacent to their free ends with aligned
apertures b of a shape and size to receive the
horn to be cut.

Eccentrically mounted upon a pivot-post,
45 as c , which bears in the plates B at a point
slightly off the longitudinal center of the same
and adjacent to the apertures b , is my im-
proved cam-shaped cutting-knife C, which is
provided with a cutting-edge d , so situated
50 with respect to the pivot-post and of such a
curvature that in operation it will gradually
enter the orbit of the annular apertures and

gradually sink into and cut through the horn. This knife C, as better illustrated in Fig. 1 of the drawings, has its edge opposite to the cut-
ting-edge d , formed into a toothed segment,
as e , for the engagement of the toothed seg-
mental head D of the operating-lever E, which
is fulcrumed upon a post at d' and plays be-
tween the plates B, as illustrated. By this
construction it will be readily perceived that
by moving the power end of the lever E in
toward the bar A the toothed head of the
said lever engaging with the toothed edge of
the cam-shaped knife will cause the same to
swing in the direction of the arrow and enter
the orbit of the annular apertures b and the
horn seated therein; and by the peculiar man-
ner of transmitting motion from the operat-
ing-lever to the knife it will be further and
readily perceived that great power and lever-
age is obtained and the operator enabled to
force the knife through a very hard substance.

Suitably fastened between the plates B at
the free ends thereof and partly surrounding
the apertures b is a curvilinear leather strip
or filling f , into which the edge of the cutting-
knife sinks in operation, whereby a complete
and smooth cut may be accomplished.

Having thus described my invention, what
I claim, and desire to secure by Letters Pat-
ent, is—

The dehorning implement described, con-
sisting, essentially, of the main bar A, the par-
allel covering or bearing plates connected to
said bar, the aligned apertures b , formed in
said plates and adapted to receive and hold a
horn, the leather filling between said plates
and partly surrounding the apertures therein,
the cam-shaped cutting-knife eccentrically
mounted between the plates adjacent to the
aligned apertures therein and having a curvi-
linear cutting-edge and a segmental toothed
edge, and the operating-lever fulcrumed be-
tween the bearing-plates and having a seg-
mental toothed head engaging the toothed
edge of the cutting-knife, substantially as and
for the purpose set forth.

In testimony whereof I affix my signature in
presence of two witnesses.

WILLIAM A. CAMPBELL.
